(57) **CLAIM**

The ornamental design for a bicycle with kickstand and docking station, as shown and described.

DESCRIPTION

FIG. 1 is a front perspective view of the left side of the bicycle with kickstand and docking station showing our new design. FIG. 2 is a rear perspective view of the right side of the bicycle with kickstand and docking station.

FIG. 3 is a top plan view of the bicycle with kickstand and docking station.

FIG. 4 is a right side elevation view of the bicycle with kickstand and docking station.

FIG. 5 is a front elevation view of the bicycle with kickstand and docking station.

FIG. 6 is a rear elevation view of the bicycle with kickstand and docking station.

FIG. 7 is a left side elevation view of the bicycle with kickstand and docking station; and,

FIG. 8 is a bottom plan view of the bicycle with kickstand and docking station.
